UNITED STATES PATENT OFFICE.

EDWARD L. RENZENBRINK, OF CANTON, OHIO.

CURTAIN BRACKET.

Application filed September 28, 1923. Serial No. 665,325.

To all whom it may concern:

Be it known that I, EDWARD L. RENZENBRINK, a citizen of the United States, residing at Canton, in the county of Stark and

5 State of Ohio, have invented certain new and useful Improvements in Curtain Brackets, of which the following is a specification.

This invention relates to a combined curtain rod and shade roller bracket, and has 10 for its objects provision of a bracket having oppositely disposed arms, one of said arms carrying a shade roller fixture, the other arm having a support for a curtain rod; the bracket being preferably adjustably mounted 15 upon a guide plate connected to the window frame; the curtain rod support comprising an inclined ovate plate; the shade roller fixture being so shaped as to permit the edge of the shade to roll out beyond the end of 20 the shade roller without engaging the fixture.

The above and other objects may be attained by constructing the bracket in the manner illustrated in the accompanying 25 drawing, in which—

Figure 1 is a plan view of the bracket showing double curtain rods and a shade roller supported thereby;

Fig. 2, an enlarged plan section of the 30 bracket;

Fig. 3, a section on the line 3—3, Fig. 1; and

Fig. 4, a perspective view of the bracket 35 provided with a slightly different form of guide plate.

Similar numerals refer to similar parts throughout the drawing.

The device preferably includes a longitudinal plate 1 having the central, longitudinally disposed, guide slot 2 therein and provided with the angular attaching portion 3 or 3^a arranged to be connected to the upper portion of the window frame 4 as by the 45 screws 5 or 5^a.

The bracket proper comprises the tubular stem 6 provided at its outer end with the oppositely disposed arms 7 and 8, and at its inner end with the arm 9 having the inturned lug 10 extended into the slot 2 of the 50 guide plate.

A clamping screw 11 is located through the tubular stem and slot 2, the head 12 thereof engaging the inner side of the guide plate and a wing nut 13 being provided upon the outer threaded end of the screw and ar-

ranged to engage the outer end of the bracket to clamp the same firmly in any desired position upon the guide plate.

Each of the inwardly disposed arms 8 of the bracket is provided at its extremity with 60 a socket 14 for the reception of the adjacent pintle of the shade roller 15 and each of the outwardly disposed arms 7 is provided at its end with an integral ovate plate 16 which is inclined outward and rearward as shown 65 in Fig. 3, the smaller end thereof being preferably down as shown in this figure.

While this particular shape of the plate 16 is preferred, it will be understood that the invention may be accomplished with the use 70 of an elliptical plate located in substantially the same position.

The curtain rod indicated generally at 17, is a flat rod of well known construction, the upper and lower edges being turned over as 75 at 18, forming channels to receive the elliptical plate 16.

In attaching the rod to the bracket, the end of the rod is tilted downward at substantially the same angle as the major axis 80 of the plate 16, and engaged over the edges of the plate as shown in dotted lines in Fig. 3, the rod being then lowered to horizontal position, as shown in full lines in said figure, the upper and lower channels upon the rod 85 frictionally engaging the plate 16 near each end thereof, frictionally holding the rod in this position.

In case where it is desired to use two curtain rods, as shown in Figs. 1 and 2, a second 90 bracket 6^a, similar to the bracket above described in every detail, with the exception of the arm 8 and shade roller fixture, is connected to the guide plate 1, in the manner above described, near the outer end thereof, 95 and the curtain rod 17^a is connected to the elliptical plate thereof.

It will be seen that the arms 8 which carry the shade roller fixtures are axially aligned with the shade roller and of considerably 100 smaller diameter than said roller.

With this construction, it will be seen that in the event the shade is accidentally rolled unevenly upon the roller, causing one side edge thereof to project beyond the end of 105 the roller, there will be no danger of this edge of the curtain contacting with the fixture and becoming damaged, this being a frequent occurrence with shade roller fixtures of the usual type.

I claim:

1. A bracket of the character described, including a stem, an angular arm upon the stem and a rearwardly and downwardly inclined, elliptical plate upon the arm arranged to be received in the end of a channel shaped curtain rod.
2. A bracket of the character described, including a stem, an angular arm upon the stem and a rearwardly and downwardly inclined, ovate plate upon the arm arranged to be received in the end of a channel shaped curtain rod.

3. A bracket of the character described, including a slotted guide plate, a tubular stem provided with a radial arm having a lug extended into the slot of the guide plate, a curtain rod support upon the tubular stem and a clamping bolt extended through the slotted guide plate and tubular stem for adjustably clamping the stem upon the guide plate.

In testimony that I claim the above, I have hereunto subscribed my name.

EDWARD L. RENZENBRINK.
